UNITED STATES PATENT OFFICE.

GEORGE B. EASTON, OF LOS ANGELES, CALIFORNIA.

KEY-POUCH.

1,110,760.

Specification of Letters Patent. Patented Sept. 15, 1914.

Application filed December 22, 1913. Serial No. 808,103.

To all whom it may concern:

Be it known that I, GEORGE B. EASTON, a citizen of the United States, residing at Los Angeles, in the county of Los Angeles, State of California, have invented new and useful Improvements in Key-Pouches, of which the following is a specification.

This invention relates to improvements in key pouches.

10 It is the object of this invention to provide an improved construction of key pouches, whereby any type of key ring can be readily attached to and removed from the pouch, and which will particularly facilitate 15 the detachment and removal of the circumferentially split type of key rings, so that the key ring may be used with or without the pouch as desired.

20 A further object is to provide a key ring attachment for key pouches which is detachable from the pouch proper, so that an old and worn pouch can be removed therefrom and the fastener attached to a new pouch.

25 The invention primarily resides in a stud formed with open ended tubular reduced end portions and enlarged shoulder portions at the base of the reduced end portions adapted to abut against the insides of the pouch 30 flaps, said reduced portions being interiorly threaded and adapted to extend through perforations in the pouch flaps, and removable binding plates formed with threaded stems adapted to be screwed into the reduced 35 ends of the stud to attach the stud between the flaps, as hereinafter more fully described, and illustrated in the accompanying drawings, in which;

40 Figure 1 is a perspective view of the key pouch showing the invention as applied. Fig. 2 is a view in vertical section on the line 2—2 of Fig. 1, as seen in the direction indicated by the arrows. Fig. 3 is a detail in perspective of the detachable key ring 45 stud, showing one of the fastening plates in a detached position.

50 In the ordinary well known key pouches the key ring retaining stud is usually permanently attached to the pouch flaps, thus rendering it difficult or impossible to remove the key ring. The present invention overcomes this difficulty and at the same time permits the pouch being detached from the stud when damaged or worn and replaced 55 by a new pouch. By this arrangement the

stud and the binding plates thereof may be made of silver or other valuable metal and suitably engraved and ornamented, as this portion of the pouch is more durable than the material of which the pouch is made and 60 will outwear a number of pouches.

In the drawings, 5 and 6 indicate the upper and lower flaps of the pouch which may be integral or connected together at one edge in book form as is common in key pouch construction, these flaps being provided with the usual snap fasteners comprising the spring stud 7 and the button 8, by means of which snap fasteners the outer edges of the flaps 5 and 6 may be secured together. 70

The present invention resides in the stud for securing a key ring 9 between the flaps 5 and 6. This stud consists of a cylindrical body portion 10, which is enlarged adjacent its ends to form annular flanges 11 and having reduced end portions or projections 12 formed centrally of the annular flanges 11. The projections 12 are designed to pass through opposed perforations 13 in the flaps 5 and 6, as shown in Fig. 2. An opening 14 extends longitudinally through the stud axially thereof and is threaded at its ends to receive correspondingly threaded stems 15 on fastening plates 16. The plates 16 are here shown as circular and formed with 80 milled peripheral edges. The outer faces of the plates 16 constitute name plates and may be engraved as desired. 85

In the application of the invention one of the projections 12 is inserted through the perforation 13 in one of the pouch flaps 5 or 6, and the plate 16 is screwed thereon to clamp or bind the flap between the plate and the shoulder 11. The key ring 9 is then placed over the stud and the other pouch flap is folded over so that the other projection 12 will pass through the perforation 13 therein. The top plate 16 is then secured in place on the stud so as to effectively bind the other flap in position. The pouch may now 100 be used in the usual manner. 95

From the foregoing it will be seen that the key ring 9 can be readily removed and attached by removing either of the fastening plates 16 and separating the pouch from the projection 12, and that the key-ring stud can be easily removed entirely from the pouch flaps by uncovering both fastening plates 16 and thereafter reattached to other pouches as desired. 105 110

What I claim is:

In a key purse, the combination with the leaves of the purse, of a detachable key-ring retaining post, interiorly threaded end projections on said post passing through the purse leaves, and removable fastening plates engageable with the projections on the binding post.

In witness that I claim the foregoing I have hereunto subscribed my name this 25th day of November, 1913.

GEORGE B. EASTON.
